DESIGN FOR A FIGURINE OR SIMILAR ARTICLE

Frances Keeney, Kansas City, Kans., assignor to Hall Brothers, Incorporated, Kansas City, Mo., a corporation of Missouri

Application March 12, 1945, Serial No. 118,431

Term of patent 14 years

(Cl. D29—23)

To all whom it may concern:

Be it known that I, Frances Keeney, a citizen of the United States, residing at Kansas City, in the county of Wyandotte and State of Kansas, have invented a new, original, and ornamental Design for Figurine or Similar Article, of which the following is the specification, reference being had to the accompanying drawing, forming part thereof.

Fig. 1 is a side view of a figurine or similar article showing my new design.

Fig. 2 is a view of the side of the figurine opposite to that shown in Fig. 1.

Fig. 3 is a front view thereof.

I claim:

The ornamental design for a figurine or similar article, as shown.

FRANCES KEENEY.
